UNITED STATES PATENT OFFICE.

JOHN E. BLAINE, JR., OF CINCINNATI, OHIO, ASSIGNOR TO THE GLOBE-WERNICKE COMPANY, OF NORWOOD, OHIO, A CORPORATION OF OHIO.

INDEX TAB.

Application filed November 21, 1921. Serial No. 516,634.

To all whom it may concern:

Be it known that I, JOHN E. BLAINE, Jr., a citizen of the United States, and residing at Cincinnati, in the county of Hamilton and 5 State of Ohio, have invented a new and useful Improvement in Index Tabs, of which the following specification is a full disclosure.

This invention relates generally to an index card for vertical filing cabinets and more particularly to an indexing strip holder for the upper margin thereof, or for other types of filing systems.

In devices of this character which are 10 shuffled over hastily and frequently by finger manipulation, the indexing strips, from continual handling, become flexed or broken, the indexing character becomes soiled or mutilated, and it is an object of the invention to overcome these two defects by providing an index strip holder which will reinforce the index card margin and which will transparently display the index character printed upon the strip while preventing said strip from becoming soiled or displaced.

Another object of the invention is to provide a structure ready for use of any desired indexing character interchangeably 20 with any particular index card.

Another object of the invention is to provide on the front face of the card margin to be indexed, a permanent transparent index strip holder, presenting the strip at the 25 proper angle of vision, enabling the index strip to be readily inserted or removed, and formed in such manner that while the holder reinforces the card margin at this handling point, the index strip when inserted in place, also reinforces, strut-like, the structure of the transparency.

These and other objects of the invention will be fully set forth in the description of the accompanying drawing, in which:

45 Figure 1 is a face view of an index card. Figure 2 is a large detailed view of the tab-holder.

Figure 3 is a cross section on line 3, 3, Fig. 2.

50 Figure 4 is a plan view of the index tab.

For convenience, an ordinary index card or sheet is shown, numbered 1, having the offset marginal bottom portion 2, of conventional form, provided with the orifice 3, 55 slidably engaging the cabinet element in

conventional manner. The upper marginal edge of this card is formed with a projecting tongue 4, for positioning and securing the index strip. It will be understood that in usage, the series of card tongues are offset in relation to one another to throw them into a single vision field. To the upper margin of the card and upon this projection 4 is secured an index strip-holder 5, formed of transparent material, such as celluloid. 60 The flexible or relatively stiff strip of celluloid is folded over the marginal portion 4 of the card, so that its opposite ends overlap upon opposite sides of the card and are secured to one another and to the intermediate 65 card by eyelet rivets 6, the intermediate portion of the strip being so folded over the tab of the card as to provide a definite shaped receptacle, approximately a triangular cross-section, and, the base of which, 7, 70 is the reading transparency properly displayed in the angle of vision. This receptacle is so formed that the angles adjacent this reading plane or panel 7 practically 75 form a seating guideway for the endwise insertion and retention of an index strip 8, ordinarily of cardboard, having an appropriate index character 9.

The utility of this device is enhanced by its extreme simplicity, enabling a substantial 80 reenforcement of the index margin of the card, making a permanent transparency for rigidly supporting and displaying the index character of an interchangeable strip, being sanitary, always legible and protected, and 85 supported upon the data face of the card.

The index holder so constituted forms a light, compact instrumentality for the card manipulation, as the tab 4 enters and extends to the top of the container, it is in 90 effect, integral with the card.

The margin of the card is reinforced from a point below the projecting tab 4, while the index insert strip, and the tab portion of the card, form two angle braces interior of the 100 container, holding it definitely on the data face of the card, so that it constitutes a sort of handle index for manipulating the card.

Another advantage of this structure is the avoidance of adhesively secured tabs or index characters or the use of index tabs which expose a printed index character to the air or the moisture of the hand, and, in addition, it is of advantage to have this index tab of a non-tearable nature. 105 110

Having described the invention, I claim:

1. An index card having a flexible strip of transparency folded over one margin and secured upon opposite surfaces of the card
- 5 reinforcing the same, the medial or fold portion of the transparency forming a receptacle open at opposite ends and approximately triangular in cross section to constitute a display panel at the proper angle of vision, an index strip placed within said receptacle against the panel and contacted at an angle by the margin of the tab, thereby holding said index strip against said panel.
- 10 an index strip placed within the said receptacle between the panel and the margin of the index card and held in place by them.
- 15 2. An index card having a tab portion at one end, a flexible strip of transparency folded over the margin of the tab and secured upon opposite surfaces of the card for

reinforcing the same, the medial or fold portion of the transparency forming a receptacle open at opposite ends and approximately triangular in cross section to constitute a display panel at the proper angle of vision, an index strip placed within said receptacle against the panel and contacted at an angle by the margin of the tab, thereby holding said index strip against said panel.

In witness whereof, I hereunto subscribe my name, as attested by the subscribing witness.

JOHN E. BLAINE, JR.

Witness:

CARL O. DIEHL.
